UNITED STATES PATENT OFFICE.

WADSWORTH D. ROY, OF BIRMINGHAM, MICHIGAN.

COMBINED ROUGE AND POWDER PUFF.

Application filed November 10, 1921. Serial No. 514,170.

To all whom it may concern:

Be it known that I, WADSWORTH D. Roy, a citizen of the United States, residing at Birmingham, county of Oakland, State of Michigan, have invented a certain new and useful Improvement in Combined Rouge and Powder Puffs, and declare the following to be a full, clear, and exact description of the same, such as will enable others skilled in the art to which it pertains to make and use the same, reference being had to the accompanying drawings, which form a part of this specification.

This invention relates to a combined rouge and powder puff, and has for its object an improved article of this type in which is incorporated a box or shell for storing an additional supply of whatever substance either puff is to be impregnated with, all being compactly and conveniently assembled, both as regards efficient use and avoidance of undue bulkiness.

In the drawings:

Figure 1 is a perspective of my improved article.

Figure 2 is a sectional view along the line 2—2 of Figure 1 and looking in the direction of the arrows there shown.

Figure 3 is a large scale sectional view taken along the line 3—3 of Figure 2 and looking in the direction of the arrows there shown.

Figure 4 is a side elevational view of a slightly modified form of the article.

A represents a central or foundation fabric layer, on each side of which is placed a puff member, as B and C. The central or foundation pad is preferably of the full rounded or perhaps slightly elliptical contour shown in Figure 1, whereas the external puff members B and C are semicircularly cut away, as at D, so that the corresponding portion of the central member A would be exposed were it not for the engagement thereabout of the spring-united storage boxes F and G, each provided with a hinged snap cover as E, and joined at their rear or outer edges by the spring H which is adapted to clamp yieldingly about the otherwise exposed portion of the central member A.

Since both boxes open inwardly, that is, facing the corresponding puff surfaces B and C, it is obvious that the entire fabric element, composed of the layers A, B, and C, can be easily bent or folded over upon itself, so that most portions of the surface

as thus folded over can be dipped into the pulverized or pasty contents of the box, thus permitting its fluffy surface to absorb sufficient thereof for its efficient application to a facial or body surface. The box portions, when the cover of each is closed, serve together as a convenient and efficient place of seizure by the hand or fingers of the user, and yet when the entire article is in the flattened-out form shown in each of Figures 1, 2 and 3, the net thickness of the two boxes only slightly exceeds the thickness of the fabric pad as a whole, thus facilitating easy storage in one's bag or pocket.

In Figure 4 I have illustrated in side elevation a slight modification from the foregoing, and with the puff portion of one surface of the article bent over for contact with the powder or similar cosmetic material in one of the boxes, as M, whose cover N has been swung open. In this form of device I omit the central or foundation fabric layer, and apply each of the boxes L and M to corresponding portions of the external puff surfaces, and unite the two by some such means as the penetrating stud and its receiving socket shown on the inner or opposing faces of the boxes.

What I claim is:

1. In combination with a centrally disposed layer, a surface layer of fluffy fabric disposed on each face of said central layer, each of said surface layers having a correspondingly positioned cut way portion which leaves the adjacent portion of the central layer exposed, a pair of outwardly opening containers located in the cut-away portions of said fabric pieces on each side of said central layer, and resilient means for holding said containers in position relatively to one another and in detachable relation about the otherwise exposed portion of said central layer.

2. In combination with a plurally laminated member having its external faces formed of puff material, each of which has a correspondingly positioned cut-away portion, containing receptacles positioned on each side of the central layer in the cut-away portions of said external layers, and means connected with each of said receptacles and adapted to engage the otherwise exposed portion of the central layer for holding said receptacles in desired position relatively thereto.

3. In combination with a central layer of

- appropriate contour, a pair of storage boxes correspondingly positioned on the opposing faces thereof, means for detachably securing said storage boxes to said central layer, and
5. surface layers of a corresponding contour to that of the central layer save for the space on each surface thereof covered by said storage boxes, the edges of said surface layers overengaging the edge of the central layer.
10. 4. In combination with a fabric pad member, powder-containing receptacles located upon corresponding edge portions of each surface thereof, and detachable means for holding said receptacles in position upon
- 15 said fabric pad member.
5. The combination, with a fabric pad, of a receptacle adapted to contain material

into which one end of said pad is adapted to be dipped, and means for detachably securing said receptacle to the opposite end of 20 said pad.

6. In combination with a fabric pad having easily absorbent surfaces, a powder-containing receptacle detachably secured against each surface of the pad along one edge in 25 position for their contents to be touched by the bent-over opposite side of the pad.

In testimony whereof, I sign this specification in the presence of two witnesses.

WADSWORTH D. ROY.

Witnesses:

WILLIAM M. SWAN,
HARRY L. WAGNER.
